ASSIGNOR TO WARREN WEBSTER & COMPANY, A CORPORATION OF NEW
JERSEY.

MODULATION-VALVE.

1,179,711.

Specification of Letters Patent. Patented Apr. 18, 1916.

Application filed September 3, 1914. Serial No. 860,107.

To all whom it may concern:

Be it known that I, JAMES L. FITTS, a citizen of the United States, and resident of Pensauken township, county of Camden, 5 and State of New Jersey, have invented an Improvement in Modulation-Valves, of which the following is a specification.

This invention relates to valves and more particularly to modulation valves for use 10 in heating systems, and consists of certain improvements which are fully set forth in the following specification and shown in the accompanying drawings which form a part thereof.

15 The object of my invention is to provide a construction wherein the valve piece and the seat therefor are arranged to regulate and proportion the volume of heating medium passing through the valve in accordance with the existing conditions.

It has for a further object to provide a valve wherein the operating parts are not exposed to or in direct contact with the heating medium whereby leakage to the out- 25 side of the valve casing is prevented and the necessity of packing for the valve stem or its adjuncts is eliminated.

30 My invention also comprehends details of construction which, together with the features above specified, will be better understood by reference to the drawings, in which:—

Figure 1 represents a sectional elevation of a modulation valve embodying my invention; Fig. 2 represents a plan of the same; Fig. 3 represents a detail showing the valve plug in side elevation; and Fig. 4 represents a modified form of valve plug.

1 designates the casing of the valve which 40 is provided with an inlet 2 and an outlet 3, between which the casing, as here shown, forms a fixed diaphragm or partition 4 provided with an opening 5 for the valve plug 6. In the preferred embodiment of the invention, the opening 5 is substantially circular in cross section and has its bounding walls straight with square edges as will be apparent.

7 designates a flanged portion of the plug 50 6 the periphery of which is provided with a plurality of substantially V-shaped graduated notches 8 and since this flanged portion fits within and traverses the valve opening 5 the resulting action is a regulated 55 opening or closing of the valve. The lower

portion 9 of the valve plug in the preferred form is substantially the shape of a frustum of a cone, the diverging periphery of which is continued in the meeting edges 10 of the aforesaid V-notches 8. It will further be noted that the lower face 11 of the flanged part 7 is partially cut away or inclined as shown at 12 so that not only is there a graduated opening of the valve plug due to its cone shape, but also a graduated 65 opening of the flanged portion as provided by the beveled portions 12.

The plug 6, in the present instance, is provided with a stem 13 having threaded engagement with the bushing 14 by which it 70 is carried. This latter element has secured thereto, in any suitable manner, a ring 15 which is interposed between the valve plug and the said bushing but projects laterally at the sides of the plug 6 in order to form 75 a seat for engagement with the partition 4 to provide for a complete closing of the opening 5. The bushing 14 in turn has threaded engagement with an internal worm sleeve 16 carried by the worm spindle 17, 80 and by which it receives the desired movement to operate the valve plug. The spindle 17 extends through the cap 18 of the casing and terminates in a stud 19 which secures the operating handle 20 in position upon the 85 exterior of said cap.

It will be understood that the portion of the spindle 17 which passes through the cap 18 is cylindrical as shown at 21 so that it is free to rotate and is also provided with a 90 collar 22, adapted to bear against the inner face of the cap 18, to prevent lineal movement of the spindle 17 during its rotation. In the present instance the cap 18 serves to secure the laterally disposed end portion 23 95 of a bellows member 24, the opposite end 25 of which is similarly clamped between the bushing 14 and the sleeve 16. The bellows is preferably corrugated to permit free end-wise expansion or contraction, and as it 100 forms a continuous encircling casing for the valve operating parts it becomes a leak-proof medium which prevents steam or water from coming into contact with the plug operating means or finding an escape by 105 way of the joint between the rotatable spindle and the cap 18.

26 designates a dial plate or graduated disk suitably fixed to the cap 18 by the nut 27 and pin 28, or like means, and carrying 110

pins or stop members 29 for the purpose of limiting the throw of the valve handle 20, it being further noted that an index pointer 30 is provided at one side of the handle and adapted to traverse the dial in a path which is limited by contact with the stops in the open and closed positions of the valve.

In Fig. 4. I have shown a modification wherein a conical valve plug 31 is employed in place of the flanged construction of the preferred form and by means of which the opening 5 may be controlled proportionately as desired.

In the operation of the valve it will be seen that as the spindle 17 is rotated the sleeve 16 is moved lineally, thereby varying the relation between the valve piece and the opening controlled by it. Since the member 24 is corrugated it is free to expand and contract under the motion of the sleeve thereby at all times forming a complete barrier or wall between the operating parts of the valve piece and the contents of the casing. Furthermore a very exact proportioning of the flow of the steam or water through the casing is made possible by the conical valve piece with its flanged portion provided with the beveled notches. In view of the fact that the bounding walls of the opening 5 are substantially at right angles to the seat face of the partition, it will be apparent that a most effective seat is provided for coaction with the flanged part of the valve piece and one which needs practically no attention or regrinding.

It will now be apparent that I have devised a novel and useful construction which embodies the features of advantage enumerated as desirable and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to protect by Letters Patent is:—

1. In a device of the character stated, a casing having an inlet and an outlet, a partition between said inlet and outlet having an opening therein, the bounding walls of said opening being substantially at right angles to a face of said partition, a valve piece comprising a flanged member a portion of which is adapted to fit within said opening and has a plurality of beveled notches in the periphery thereof and another portion of conical shape extending from said flanged member, an annular closure adapted to seat upon said partition to entirely close said opening according to requirements, and means to shift said valve

piece and said closure to regulate the flow through said opening or shut it off altogether.

2. In a device of the character stated, a casing having an inlet and an outlet, a partition between said inlet and outlet having an opening therein, a valve piece comprising a flange part adapted for sliding movement within said opening and having a plurality of beveled notches in the periphery thereof, and a conically shaped member at one side of said flange part adapted to enter said opening in advance of said flange part, an annular closure carried by said valve piece adapted to seat upon said partition to entirely close said opening according to requirements, a threaded sleeve connected to said valve piece, a spindle having threaded engagement with said sleeve and extending exterior of said casing, means to prevent longitudinal movement of said spindle, a handle for causing rotation of said spindle to shift said sleeve, valve piece and closure toward or away from said opening, and means inclosing said sleeve to separate its parts from the contents of said casing.

3. In a device of the character stated, a casing having an inlet and an outlet, a partition between said inlet and outlet having an opening therein, a valve piece adapted for sliding movement within said opening and comprising a conically shaped member, an annular closure carried by said valve piece adapted to seat upon said partition to entirely close said opening according to requirements, a threaded sleeve connected to said valve piece, an apertured cap secured to said casing, a bellows fold member having an outwardly extending flange at one end clamped between said cap and said casing, and an inwardly disposed flange clamped between said sleeve and said valve piece, said bellows member forming a leak-proof expansible wall between said sleeve and the medium controlled by said valve piece, a spindle having threaded engagement with said sleeve and extending through the aperture of said cap, a dial plate fixed against rotation upon said cap, a nut having threaded engagement with a portion of said cap for clamping said dial plate in operative position, a collar secured to said spindle and abutting the inner face of said cap, and an operating handle provided with an index pointer secured to the projecting end of said spindle and arranged to abut said cap to prevent axial movement of said spindle, and means to limit the rotation or movement of said handle.

4. In a device of the character stated, a casing having an inlet and an outlet, a partition between said inlet and said outlet having an opening therein, a valve piece having a truncated conical portion pro-

vided with a flange part encircling a portion of said truncated conical portion said flange part having a plurality of beveled notches formed in the periphery thereof, 5 the meeting edge of the walls of the respective notches lying in the surface of the truncated conical portion, an annular closure seated upon said flange part and adapted to entirely close said partition 10 opening in one position, operating means for said valve piece and closure extending exterior of said casing, and a bellows fold member surrounding a portion of said operating means within said casing to form 15 a leak-proof expandible wall completely separating the operating means from the medium controlled by said valve piece.

5. In a device of the character stated, a casing having an inlet and an outlet and 20 a partition between said inlet and outlet having an opening therethrough, combined

with a valve having a lower conical part of less diameter than said opening, an upper flange of greater diameter than the opening through the partition, and an intermediate flange of the same diameter as the said opening interposed between the upper flange and the conical part, and said intermediate flange having a plurality of notches about its perimeter said notches 25 being largest at the bottom and tapering off to nothing at the top and differing in depth so that their innermost wall portions are substantially continuous with the conical walls, and means for operating the 30 valve piece.

In testimony of which invention, I hereunto set my hand.

JAMES L. FITTS.
